(57) **CLAIM**

The ornamental design for a handheld gyroscope fidget toy, as shown and described.

DESCRIPTION

FIG. 1 is a front perspective view of a handheld gyroscope fidget toy;

FIG. 2 is a front elevation view thereof, the rear elevation view being a mirror image thereof;

FIG. 3 is a left side elevation view thereof, the right side elevation view being a mirror image thereof; and,

FIG. 4 is a top plan view thereof, the bottom plan view being a mirror image thereof.

The broken lines shown in the drawings depict portions of a handheld gyroscope fidget toy that form no part of the claimed design.
